(57) **CLAIM**

The ornamental design for a cartridge, as shown and described.

DESCRIPTION

FIG. 1 is a top left perspective view of the cartridge;
 FIG. 2 is a front view of the cartridge, taken from the frame of reference of FIG. 1;
 FIG. 3 is a rear view of the cartridge, taken from the frame of reference of FIG. 1;
 FIG. 4 is a right side view of the cartridge, taken from the frame of reference of FIG. 1;
 FIG. 5 is a left side view of the cartridge, taken from the frame of reference of FIG. 1;
 FIG. 6 is a top view of the cartridge, taken from the frame of reference of FIG. 1;
 FIG. 7 is a bottom view of the cartridge, taken from the frame of reference of FIG. 1; and,
 FIG. 8 is a bottom right perspective view of the cartridge, taken from the frame of reference of FIG. 1.
